AUTOMATIC TIME SWITCH CLOCK

Adrian Martin, New York, N. Y.

Application November 22, 1938, Serial No. 241,809

8 Claims. (Cl. 200—38)

This invention relates to new and useful improvements in an automatic switch clock.

More specifically, the invention relates to an improved automatic switch clock characterized by the provision of separate mechanisms controlled by a conventional clock mechanism for closing an electrical circuit at a predetermined time and for opening the electrical circuit at a predetermined time.

10 Still further the invention proposes the construction of an "on" cycle mechanism of a particular construction associated with the clock mechanism in a particular manner to cause the electrical circuit to be completed when the clock mechanism reaches a predetermined time.

15 Another object of this invention is the provision of an "off" cycle mechanism connected with the clock mechanism in a particular manner to open the circuit when the clock mechanism reaches a predetermined time.

20 A further object of this invention is to characterize each of the cycle mechanisms with a shaft rotatively and slidably mounted through the frame of a clock and which projects from the 25 face side thereof and has a spindle mounted thereon and extended to the interior of said clock in a particular manner to be used for setting specific times at which the mechanisms are to open and close the said circuit.

25 Still further the invention proposes the provision of a pointer radially mounted on said shaft and extended through a slot formed in said spindle in a particular manner to register on a calibrated scale formed on the face of the clock for 30 setting the mechanism at the predetermined time.

35 Another object of this invention is the provision of a gear with a hub freely mounted on said shaft to rotate and move longitudinally theron and having the free end of its hub in end contact 40 with said spindle with a cam mounted on said shaft and engageable upon the end of said hub and into a cut-out formed in said hub when said predetermined time is reached in a particular manner to permit the circuit to be opened or 45 closed.

45 Another object of this invention is the provision of associated contacts mounted on said gear and the face of the clock in a particular manner 50 to control the operation of said circuit in the different longitudinal positions of the gear.

55 Another object of this invention is the provision of a friction means for holding said shaft against rotating while the gear is being rotated to reach said predetermined time to prevent said

shaft from being turned from said predetermined time.

For further comprehension of the invention, and of the objects and advantages thereof, reference will be had to the following description 5 and accompanying drawing, and to the appended claims in which the various novel features of the invention are more particularly set forth.

In the accompanying drawing forming a material part of this disclosure:—

10 Fig. 1 is a perspective view of a clock having an improved automatic switch constructed according to this invention.

Fig. 2 is a vertical sectional view substantially on the line 2—2 of Fig. 1.

15 Fig. 3 is a horizontal sectional view on the line 3—3 of Fig. 2.

Fig. 4 is a sectional view of one of the clips per se.

20 Fig. 5 is a vertical sectional view through the "on" cycle mechanism shown on the right hand side of Fig. 2.

Fig. 6 is a sectional view on the line 6—6 of Fig. 2.

25 Fig. 7 is an enlarged detailed view on the line 7—7 of Fig. 2.

The improved automatic switch clock is to be used in conjunction with a clock including a housing 10 consisting of a tubular side wall 10^a and end walls 10^b. The end walls 10^b are inserted into the ends of the tubular side wall 10^a and are held in position by means of screws 11 which pass therethrough and threadedly engage brackets 12 mounted on the inner face of the tubular side wall 10^a. The bottom end wall 10^b 35 is formed with a plurality of foot members 13 upon which the clock body rests and which are held in position by means of screws 14.

The clock mechanism includes separate frame sections 15, 16 and 17. The frame section 15 40 is attached to the inner face of the side walls 10^a of the clock body by means of brackets 18 upon which the peripheral edge of the frame section 15 is rested. Screws 19 are passed through the frame section 15 and into the brackets 18 45 for maintaining the section in position upon the said brackets. The frame section 16 is connected to the frame section 15 by means of brackets 20 which are extended between the adjacent faces thereof. Likewise, the frame section 17 is connected to the frame section 16 by means of brackets 21 50 which extend between the adjacent faces of these frame sections.

A clock face 22 is provided with a plurality of numerals 23 around the peripheral edge there- 55

of which are adapted to be viewed through an opening 10^{aa} formed on one side of the side wall 10^a. The clock face is formed with an internal flange 24 which extends radially inwards and is superimposed above the edge of the frame section 17. A raceway 25 having a plurality of ball bearings 26 is disposed between the adjacent faces of the flange 24 and the frame section 17 for rotatively supporting the clock face 22 upon the frame section 17. The bottom wall of the clock face 22 is formed with a downwardly extending projection 27 which extends into a cutout formed in a block 28 securely attached to the bottom end wall 10^b of the clock body 10 by means of screws 29.

The superimposed faces of the projection 27 and the block 28 are provided with a raceway 30 having ball bearings 31 to permit the projection to turn freely upon the block 28. This projection acts to centrally locate the clock face 22 within the body 10 and to prevent the same from swaying and being displaced from the frame section 17.

A means is provided for driving the clock face 22 and includes a tube 32 which extends through an opening formed in the frame section 16 and which has its bottom end resting on the top face of the frame section 17. A gear 33 is mounted on the tube 32 intermediate of its ends. The bottom end of the tube 32 is not attached to the frame 17 and merely rests freely thereon. A shaft 35 has its upper end rotatively supported in a bearing 36 attached to the bottom face of the frame section 16. The other end of the shaft 35 passes freely through an opening formed in the frame section 17. A conventional clock spring mechanism including a casing 37 is mounted on the shaft 35 and has a clock spring, not shown on the drawing housed therein, as is customarily adapted to be wound by turning the shaft 35. A gear 38 is associated with the spring mechanism as is driven thereby and meshes with gear teeth 33^a formed on the hub of the gear 33.

A large gear 39 has a hub 39^a rotatively mounted on the tube 32 by pins 40 which engage in a peripheral groove 32^a in the tube 32. The upper end of the hub 39^a is formed with internal gear teeth which mesh with a small pinion 41. This pinion 41 is mounted upon a spindle 42 which extends through the tube 32 to the exterior of the clock body 10 through an opening formed in the top end wall 10^b. The bottom end of the spindle 42 is formed with a conical-shaped gear 43 which is engageable into a conical-shaped gear cutout 44 formed in a block 45 which is securely attached to the center portion of the clock face 22.

When the device is in operation the spring contained within the casing 37 will cause the gear 38 to be rotated, independently of the shaft 35 and cause the gear 33 to be rotated. The gear 33 will then rotate the tube 32 which in turn will rotate the spindle 42 through the medium of the gear 41 to cause the clock face 22 to be rotated. The gear 33 is formed with gear teeth 33^b which are adapted to mesh with a conventional clock mechanism including an escapement not shown on the drawing, for preventing the spring, not shown on the drawing, contained within the casing 37 of the spring mechanism device from unwinding too rapidly to cause the clock face to be rotated at the proper rate of speed to move one complete revolution every 12 hours.

The upper end of the spindle 42 extends from the end of the clock body 10 and is formed with

a knob 46 formed with threads upon which a key 47 is adapted to be engaged. The key 47 is provided for permitting the device to be wound when the spring contained within the spring mechanism becomes unwound. When it is desired to wind the device the key 47 is engaged on the knob 46 and the spindle 42 is pulled outwards, disengaging the gear 41 from the internal gear teeth formed on the hub 39^a and also disengaging the conical gear 43 from the conical gear opening 44 formed in the block 45. A gear 48 is mounted on the lower end of the spindle 42 above the conical-shaped gear 43 and is adapted to mesh with a complementary gear 49 mounted on the lower end of the shaft 35 when the spindle 42 is moved outwards.

A means is provided for holding the spindle 42 in its pulled out position and comprises a grooved wheel 50 which is mounted upon an intermediate portion of the spindle 42 which is adapted to be snapped into a pair of clips when the spindle 42 is urged outwards. These clips comprise hollow bodies 51 which are mounted upon the bottom face of the frame section 15. Half circular elements 52 extend from the ends of the bodies 51 and are engageable into the peripheral groove 50^a in the wheel 50 when the spindle is moved upwards.

Springs 53 are located within the bodies 51 and urge the half circular elements 52 into their extended positions. The half circular elements 52 are formed with flanges 52^a located within the bodies and which prevent the elements 52 from being completely urged out of the bodies 51 by the springs 53. Thus when the spindle 42 is moved outwards and the wheel 50 is engaged into the clips it will maintain the gears 43 and 49 in an inter-engaged position for causing the shaft 42 to be rotated independently of the tube 32 for turning the shaft 35 when the key 47 is rotated.

A ratchet wheel 54 is mounted upon the shaft 35 and is engageable by a pawl 55 which permits the shaft 35 to be rotated independently of the casing 37 and the gear 38 for winding the spring contained within the casing 37. The casing 37 of the spring mechanism is supported on a bracket 37^a for preventing the spring from unwinding when the gears 43 and 49 are disconnected. After the winding operation is completed the spindle 42 is again urged inwards to disconnect the gears 43 and 49 and return the gears 41 and 43 to their normal positions to cause the clock face 22 to be rotated by the clock mechanism.

There is an "on" cycle and an "off" cycle associated with the clock mechanism to cause an electrical circuit to be completed at a predetermined time and to cause the same electrical circuit to be opened at another predetermined time. The "on" cycle mechanism comprises a shaft 56 rotatively extended through openings formed in the frame sections 16, 15 and the top wall 10^b of the clock body 10. A spindle 57 is mounted on the extended end of the shaft 56 and is extended into the clock through an opening formed in the end wall 10^b and rotatively extends through an opening formed in the frame section 15. A pointer 58 extends through a longitudinal slot 57^a formed in the spindle 57 and has its inner end mounted on the shaft 56 for locking these parts for unitary turning.

Furthermore, the pointer 58 extends over a calibrated scale 59 formed on the outer face of the end wall 10^b for permitting the shaft 56 to

to be moved to a predetermined time at which it is desired to complete the electrical circuit.

A gear 60 having a hub 60^a is freely mounted on the shaft 56 to rotate and move longitudinally thereon and has the free end of the hub 60^a in contact with the end of the spindle 57 as shown in Fig. 5. A cam 61 is mounted on the shaft 56 and extends into a longitudinal slot 60^{aa} formed in the hub 60^a of the gear 60 to lock the shaft 56 and the hub 60^a together for unitary turning in the closed position of the circuit. The cam 61 is engageable when the spindle 57 is moved longitudinally inwards, into a short longitudinal slot 57^b formed in the inner end of the spindle 57; and in turning the spindle, the cam 61, when located within the slot 57^b, will ride on the upper end of the hub 60^a for holding the "on" mechanism in position in which the circuit will be opened until the predetermined time is reached permitting the cam to engage into the slot 60^{aa} for closing the said circuit.

A resilient means is provided for urging the gear 60 outwards to maintain the end of the hub 60^a in contact with the end of the spindle 57. This means comprises a spring 62 coaxially mounted upon a portion of the shaft 56 and which operates between the adjacent faces of the gear 60 and the frame section 16.

Associated contacts are mounted on the gear 60 and the frame of the clock to control the closing of the circuit in the different longitudinal positions of the gear 60. In the "on" cycle mechanism the associated contacts comprise a disc-shaped contact member 63 which is provided with a centrally located opening 63^a through which the spring 62 and the end of the shaft 56 extend. The top face of the disc-shaped contact 63 is provided with a pair of upwardly extending arms 64 which pass through and are fixedly maintained in positions by means of friction insulation members 65 constructed of rubber or other similar material and mounted upon the gear 60. The upper ends of the arms 64 are provided with contact members 64^a which are adapted to engage a contact 66 when the gear 60 is urged upwards by means of the spring 62 for completing the circuit.

The electrical circuit 67 has a lead 67^a which is connected to a pin 68 mounted on the frame section 16 and insulated therefrom by means of an insulation member 69. A leaf spring 70 is also mounted on the pin 68 and engages the bottom face of the contact 63 in all of its adjusted positions for completing the circuit 67 at this point. The current passes from the spring 70 through the plate 63 and the arm 64 to the contact 66 when the gear 60 is moved upwards. A lead 67^b extends from the contact 66 to the "off" cycle which will be described in detail hereinafter. The contact 66 is mounted on the frame section 16 and is insulated therefrom by means of an insulation member 68 which is interposed between the adjacent faces thereof.

The frame section 16 has a friction member 70 mounted upon the bottom face thereof and through which the shaft 56 extends. The bottom face of the friction member 70 is formed with an inwardly extending conical-shaped opening 70^a. A friction element 71 is mounted on the bottom end of the shaft 56 and is maintained in position thereon by means of a nut 72 and is engageable into the conical-shaped opening 70^a when the cam 61 is resting on the end of the hub 60^a to prevent the shaft 56 from turning with the gear 60 until the cam 61 engages into the cutout 60^{aa}.

When the cam 61 engages into the cutout 60^{aa} the shaft 56 moves downwards to disengage the friction elements 71 from the opening 70 to free the shaft so that it may rotate with the gear 60.

The gear 60 is connected to the gear 39 through the medium of a gear 73 which is mounted on the top face of the frame section 16 by means of a pin 74. A gear 32^b is fixedly mounted on the tube 32 and meshes with a pinion 73' freely mounted on the pin 74 below the gear 73. A pawl 73^a operates between the gears 73 and 73' to cause them to be rotated in unison to rotate the gear 39 which in turn will rotate the spindle 42 through the medium of the gear 41 to rotate the clock face 22.

The operation of the "on" cycle is as follows:

The spindle 57 is manually urged downwards causing the pointer 58 to be rested upon the face of the end section 10^b for preventing the shaft 56 from moving inwards. This movement of the spindle 57 causes the gear 60 to be moved downwards compressing the spring 62 and moving the arms 64 downwards to break the contact between the members 64^a and the contact 66. This movement of the spindle 57 causes the cam 61 to move out of the cutout 60^{aa} into the cutout 57^b in the bottom end of the spindle 57. This frees the shaft 56 from the gear 60 permitting the same to be rotated to cause the cam 61 to ride upon the top end of the hub 60^a. The pointer 58 is then rotated to the desired position at the time it is desired to have the circuit completed by aligning it with the proper hour numeral of the calibrated scale 59.

It will be noted that the pointer 58 and the cam 61 are in superimposed positions one above the other upon the shaft 56 so that the cam 61 will assume the same position with relation to the scale 59 as the pointer 58. When the spindle 57 is released after the desired time position has been reached the spring 62 will urge the gears 60 upwards and because the cam 61 is resting on the upper end of the hub 60^a formed on the gear 60, the shaft 56 will be urged outwards to cause the friction elements 71 to be engaged into the opening 70^a formed in the friction member 70 for preventing the shaft 56 from rotating when the gear 60 is rotated through the medium of the gear 73.

When the cutout 60^{aa} reaches the predetermined time, indicated by the pointer 58, the cam 61 will engage into the cutout 60^{aa} permitting the gear 60 and the spindle 57 to be moved upwards by means of the spring 62 to complete the electrical circuit and permit the shaft 56 and the spindle 57 to rotate with the gear 60 to maintain the circuit in its closed position.

The "off" cycle for opening the electrical circuit when a predetermined time is reached is similar to the "on" cycle mechanism except that the contacts are at the lower part of the device and are open when the device operates. In the "on" cycle mechanism the contacts are located at the top of the device and close the circuit when the gear 60 and hub 60^a move upwards.

To hand set the clock face 22 to indicate the proper time the key 47 is removed from the knob 46 and the spindle 42 is urged inwards to engage the gear 43 into the cutout 44 so that when the knob 46 is rotated it will cause the clock face 22 to be rotated to align the proper time numeral 23 with the cutout 10^{aa} formed in the body 10. This rotation of the spindle 42 must be in a direction which will permit the gears 73

and 91 to rotate past the pawls 73^a and 91^a permitting the gears 73' and 91' to remain still.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In combination with a clock, a shaft rotatively and slidably mounted through the frame 15 of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated 20 scale on the face of the clock, a gear with a hub freely mounted on said shaft to rotate and move longitudinally and having the free end of its hub in end contact with said spindle, a cam mounted on said shaft and extending into a longitudinal slot in said hub to lock these parts for unitary turning and engageable when said spindle is moved longitudinally inwards into a short longitudinal slot in the inner end of said 25 spindle and in a turned position of the spindle engageable on the top edge of said hub, resilient means urging said gear outwards, associated contacts mounted on said gear and the frame of the clock to control a circuit in the different 30 longitudinal positions of said gear, a friction member mounted on the frame of the clock, and a friction element mounted on said shaft and engaging said friction member in a position of said shaft when said cam is on the edge of the hub for holding the shaft non-rotative, said 35 gear being connected with the clock mechanism in a manner to cause said gear to be rotated for aligning the cutout therein with said cam when said cutout reaches the predetermined position similar to the setting of said pointer.

2. In combination with a clock, a shaft rotatively and slidably mounted through the frame 40 of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated 45 scale on the face of the clock, a gear with a hub freely mounted on said shaft to rotate and move longitudinally and having the free end of its hub in end contact with said spindle, a cam mounted on said shaft and extending into a longitudinal slot in said hub to lock these parts for unitary turning and engageable when said spindle is moved longitudinally inwards into a short longitudinal slot in the inner end of said 50 spindle and in a turned position of the spindle engageable on the top edge of said hub, resilient means urging said gear outwards, associated contacts mounted on said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, said 55 automatic switch being characterized by an "on" cycle for causing said circuit to be completed when said predetermined position is reached, and an "off" cycle for causing said circuit to be broken when said predetermined position is 60 reached.

70 3. In combination with a clock, a shaft rotatively and slidably mounted through the frame of said clock and projecting from the face side of the clock, a spindle mounted on the extended 75

calibrated scale similar to that assumed by the pointer.

5 3. In combination with a clock, a shaft rotatively and slidably mounted through the frame of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated 10 scale on the face of the clock, a gear with a hub freely mounted on said shaft to rotate and move longitudinally and having the free end of its hub in end contact with said spindle, a cam mounted on said shaft and extending into a longitudinal slot in said hub to lock these parts for unitary turning and engageable when said spindle is moved longitudinally inwards into a short longitudinal slot in the inner end of said 15 spindle and in a turned position of the spindle engageable on the top edge of said hub, resilient means urging said gear outwards, associated contacts mounted on said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, said gear being connected with the clock mechanism in a manner to cause said gear to be rotated for aligning the cutout therein with said cam when said cutout reaches the predetermined position 20 similar to the setting of said pointer.

4. In combination with a clock, a shaft rotatively and slidably mounted through the frame of said clock and projecting from the face side of the clock, a spindle mounted on the extended 25 end of said shaft and extending into said clock, a pointer radially mounted on said shaft and extending through a longitudinal slot in said spindle to lock these parts for unitary turning and furthermore extending over a calibrated 30 scale on the face of the clock, a gear with a hub freely mounted on said shaft to rotate and move longitudinally and having the free end of its hub in end contact with said spindle, a cam mounted on said shaft and extending into a longitudinal slot in said hub to lock these parts for unitary turning and engageable when said spindle is moved longitudinally inwards into a short longitudinal slot in the inner end of said 35 spindle and in a turned position of the spindle engageable on the top edge of said hub, resilient means urging said gear outwards, associated contacts mounted on said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, said 40 automatic switch being characterized by an "on" cycle for causing said circuit to be completed when said predetermined position is reached, and an "off" cycle for causing said circuit to be broken when said predetermined position is 45 reached.

5. In combination with a clock, a shaft rotatively and slidably mounted through the frame of said clock and projecting from the face side of the clock, a spindle mounted on the extended 50

- end of said shaft and extending into said clock, a pointer radially mounted on said shaft and extending through a longitudinal slot in said spindle to lock these parts for unitary turning and furthermore extending over a calibrated scale on the face of the clock, a gear with a hub freely mounted on said shaft to rotate and move longitudinally and having the free end of its hub in end contact with said spindle, a cam mounted 5 on said shaft and extending into a longitudinal slot in said hub to lock these parts for unitary turning and engageable when said spindle is moved longitudinally inwards into a short longitudinal slot in the inner end of said spindle and 10 in a turned position of the spindle engageable on the top edge of said hub, resilient means urging said gear outwards, associated contacts mounted on said gear and the frame of the clock to control a circuit in the different longitudinal 15 positions of said gear, a friction member mounted on the frame of the clock, and a friction element mounted on said shaft and engaging said friction member in a position of said shaft when said cam is on the edge of the 20 hub for holding the shaft non-rotative, said automatic switch being characterized by an "on" cycle for causing said circuit to be completed when said predetermined position is reached, and an "off" cycle for causing said circuit to be 25 broken when said predetermined position is reached, said automatic contacts of said "on" cycle comprising a disc-shaped contact supported upon said gear and having arms extending through said gear and insulated therefrom, a 30 spring mounted upon a portion of said clock and engageable against one face thereof in all of the adjusted positions of said gear, and contact elements formed on the upper ends of said arms, a contact mounted on said clock and above 35 said gear and adapted to be contacted by said contact members when said gear is moved upward by the use of said spring when said cam engages the cutouts in said hub.
6. In combination with a clock, a shaft 40
- 45
- rotatively and slidably mounted through the frame of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated scale on the face of the clock, a gear with a hub freely mounted on said shaft to rotate and move longitudinally and having the free end of its hub in end contact with said spindle, a cam mounted 50 on said shaft and extending into a longitudinal slot in said hub to lock these parts for unitary turning and engageable when said spindle is moved longitudinally inwards into a short longitudinal slot in the inner end of said spindle and in a turned position of the spindle engageable on the top edge of said hub, resilient means urging said gear outwards, associated contacts mounted on 55 said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, and means for permitting the clock mechanism to be wound for driving 60 said gear.
7. In combination with a clock, a shaft 65
- rotatively and slidably mounted through the frame of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated scale on the face of the clock, a gear with a hub freely mounted on said shaft to rotate and move longitudinally and having the free end of its hub in end contact with said spindle, a cam mounted 70 on said shaft and extending into a longitudinal slot in said hub to lock these parts for unitary turning and engageable when said spindle is moved longitudinally inwards into a short longitudinal slot in the inner end of said spindle and in a turned position of the spindle engageable on the top edge of said hub, resilient means urging said gear outwards, associated contacts mounted on said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, and means for permitting the clock mechanism to be wound for driving 75 said gear.

ing said circuit to be broken when said predetermined position is reached, said contact members for said "off" cycle mechanism comprising a disc-shaped contact member, upwardly extending arms mounted on one of the faces of said contact member and extending through insulation members formed on said gear for connecting said contact plate to said gear, a stop element on said clock above said gear and against which said arms are adapted to abut for limiting upward movement of said gear, and contact members mounted on said clock and engageable by said contact member, when said cam engages on the end of said hub.

7. In combination with a clock, a shaft 15 rotatively and slidably mounted through the frame of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated scale on the face of the clock, a gear with a hub freely mounted on said shaft to rotate and move longitudinally and having the free end of its hub in end contact with said spindle, a cam mounted on 20 said shaft and extending into a longitudinal slot in said hub to lock these parts for unitary turning and engageable when said spindle is moved longitudinally inwards into a short longitudinal slot in the inner end of said spindle and in a turned position of the spindle engageable on the top edge of said hub, resilient means urging said gear outwards, associated contacts mounted on 25 said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, and means for permitting the clock mechanism to be wound for driving 30 said gear.

8. In combination with a clock, a shaft 35

40

rotatively and slidably mounted through the frame of said clock and projecting from the face side of the clock, a spindle mounted on the extended end of said shaft and extending into said clock, a pointer radially mounted on said shaft and extending through a longitudinal slot in said spindle to lock these parts for unitary turning and furthermore extending over a calibrated scale on the face of the clock, a gear with a hub freely mounted on said shaft to rotate and move longitudinally and having the free end of its hub in end contact with said spindle, a cam mounted on 50 said shaft and extending into a longitudinal slot in said hub to lock these parts for unitary turning and engageable when said spindle is moved longitudinally inwards into a short longitudinal slot in the inner end of said spindle and in a turned position of the spindle engageable on the top edge of said hub, resilient means urging said gear outwards, associated contacts mounted on 55 said gear and the frame of the clock to control a circuit in the different longitudinal positions of said gear, a friction member mounted on the frame of the clock, and a friction element mounted on said shaft and engaging said friction member in a position of said shaft when said cam is on the edge of the hub for holding the shaft non-rotative, and means for permitting the clock mechanism to be wound for driving 60 said gear.

5 gear, said means comprising a spindle having one of its ends extended into said clock and the other of its ends extended from said clock, said end contained within said clock having a gear mounted thereon, a shaft rotatively supported within said clock, a clock spring device mounted on said shaft, a gear mounted on one end of said shaft

and engageable with said gear, and a key engageable on the extended end of said spindle for rotating said spindle to correspondingly rotate said shaft to wind the spring contained within said device.

5 ADRIAN MARTIN.
